DESIGN FOR A PHONOGRAPH PICKUP ARM

Kurt Emde, Itasca, and George B. Vernier, Chicago, Ill., assignors to Zenith Radio Corporation, Chicago, Ill., a corporation of Illinois

Application May 23, 1945, Serial No. 119,692

Term of patent 14 years

(Cl. D26—14)

To all whom it may concern:

Be it known that we, Kurt Emde and George B. Vernier, both citizens of the United States of America and residing respectively at Itasca, DuPage County, State of Illinois and Chicago, Cook County, State of Illinois, have invented a new, original, and ornamental Design for a Phonograph Pickup Arm or Similar Article, of which the following is a specification, reference being had to the accompanying drawings, forming a part thereof.

Figure 1 is a top perspective view of a phonograph pickup arm showing our new design; Figure 2 is a side perspective view; Figure 3 is a front elevational view; and Figure 4 is an enlarged fragmentary view of the front end portion of the design.

We claim:

The ornamental design for a phonograph pickup arm or similar article, substantially as shown.

KURT EMDE.

GEORGE B. VERNIER.
